INVENTOR,

F. G. Johnson

UNITED STATES PATENT OFFICE.

FRANK G. JOHNSON, OF BROOKLYN, NEW YORK.

BALLASTING.

SPECIFICATION forming part of Letters Patent No. 284,210, dated September 4, 1883.

Application filed December 22, 1882. (No model.)

To all whom it may concern:

Be it known that I, FRANK G. JOHNSON, a citizen of the United States, residing in the city of Brooklyn, county of Kings, and State 5 of New York, have invented a new and useful Method of Ballasting Boats, of which the following is a specification.

My invention relates to the ballasting of all kinds of boats, whether propelled by steam or 10 wind; but it relates more particularly to vessels propelled by steam—as steamboats, steamships, and steam-yachts—for the reason that steam is employed in connection with my invention. In case of applying my invention to 15 sailing-vessels, a small amount of steam would need to be provided.

It is well known that steamboats, especially those that are employed chiefly or in part for 20 carrying passengers, need to be frequently ballasted, for the reason that the passengers move from one side to the other of the boat, while all vessels need to be more or less trimmed or ballasted from time to time, as the wind may blow against them from different directions. 25 This ballasting heretofore has been accomplished by means of moving from one side to the other of the boat what are known as “heavy-chain boxes,” which are often weighted with tons of pig-iron. There are serious ob-

30 jections to this method of temporarily ballasting of boats: First, they are “dead-weights;” second, it is heavy work to move them; third, by the nature of things they must be drawn on an upgrade; fourth, they damage the deck 35 of the boat; fifth, when the boat is much down on one side the chain boxes cannot be moved, and just at the time when the ballasting is most needed, even to the saving of the boat from peril and destruction; sixth, in case of a 40 heavy lurching of the boat these chain boxes slide and dash through the side of the boat and go overboard; seventh, these boxes often need to be moved just at the time the boat-hands are needed for other work to save the 45 boat from peril.

To obviate these objections and place the ballasting of boats within the power of the pilot, who always knows when the boat is out of trim, is the object of my invention, which I 50 attain by the means illustrated in the accompanying drawing.

The drawing represents a vertical transverse section of a steamboat about midships, in which A A represent the lower or main deck; B B, the saloon-deck; C C, the hurricane-deck; F F, the floor in the hull of the boat; E E, the boiler; D D, the pilot-house. Extending from the boiler E E to the lower side of the saloon-deck B B is an iron steam-pipe, K, which extends in opposite directions, 55 as J J, and connects with the water-tanks H H, one on either side of the boat, placed as far from the vertical center of the boat as practicable. These tanks are made preferably of light boiler-iron, and of sufficient size to hold 60 as much water as may be required to ballast the boat. G G are supply and discharge pipes, the lower ends of which extend down through the keel of the boat at G', and the upper ends of which enter one into one of the tanks H 65 and the other into the other tank. The steam-pipes J J are provided with cut-off cocks j" j", which are operated by the handles j j. The supply and discharge pipes G G are provided with cut-off cocks g" g", which are operated by the handles g g. L L are air-pipes 70 to admit air into the tanks H H. The cut-off cocks of these air-pipes are at and connected with the handles l l.

Having designated the various parts of my 80 device, I will now explain the function of each, and their combined operation to accomplish the ballasting of boats.

Supposing both tanks H H to be empty of 85 everything but air, and that the pilot desires to trim the boat by adding weight to the right-hand side. To do this he first has to turn the right-hand cock j, (the right-hand cock g" being already open,) which will allow steam from the boiler to enter the right-hand tank and 90 drive the air therefrom down through the right-hand pipe G. This being done, (which takes but a moment,) the pilot now closes the right-hand cock j, whereupon the steam in the right-hand pipe G and tank H will be instantly condensed by the cold water in which the boat 95 floats, producing a vacuum in said pipe and tank, which of course will cause the water to rush into and fill the said tank with a force equal to fifteen pounds to the square inch. The 100 pipe G being about six inches in diameter the tank H is almost instantly filled. Should it

not be necessary to fill the tank H full to properly trim the boat, the pilot stops the flow of the water into the tank by closing the right-hand cock g'' whenever the boat is in perfect trim. When in time the boat needs to be again trimmed, the pilot will admit more water by again opening the right-hand cock G, provided more weight is still required on this side; but in the event this side is already too heavy, he will first open the right-hand air-cock l, and then the right-hand cock G, whereupon the water in the tank will flow out through the pipe G. Should both tanks be empty, and the left-hand side of the boat should need to be weighted, it will be accomplished in the same manner as above described, as the apparatus is the same on either side of the boat.

By means of my invention it will be seen that the pilot has control of trimming or ballasting the boat, and all the above objections, inseparable from the present method, are obviated.

I do not limit myself to any particular arrangement of the various pipes and cocks and handles of the cocks, whereby only the pilot can work the device, as they may be so arranged that the deck-hands or the engineer can work the faucets or cocks, should it be preferable so to do. Neither do I limit myself to placing the cocks $j'' j''$ in any particular posi-

tion between the boiler and the tanks H H; nor do I limit myself to placing the cocks $g'' g''$ in any particular position, only so that they are between the water in which the boat floats and the tanks H H.

I am aware that the lifting of water for various purposes by means of a vacuum produced by condensation of steam is not new. Therefore I do not claim the mere raising of water by means of a vacuum irrespective of its application to any particular purpose; but

What I do claim as new, and desire to secure by Letters Patent, is—

1. In various boats, for ballasting the same, the combination of the steam-boiler E E, the steam-pipes J J, having the cut-off cocks $j'' j''$, the tanks H H, and water-pipes G G, having the cut-off cocks $g'' g''$, substantially in the manner and for the purposes described.

2. In various boats, for ballasting the same, the combination of the steam-boiler E E, the steam-pipes J J, having the cut-off cocks $j'' j''$, the tanks H H, water-pipes G G, having the cut-off cocks $g'' g''$, and air-pipes L L, having the cut-off cocks l l, substantially in the manner and for the purposes set forth.

FRANK G. JOHNSON.
